UNITED STATES PATENT OFFICE.

JOHN H. RESE, OF WASHINGTON, DISTRICT OF COLUMBIA.

BOTTLE-CAPPING MACHINE.

1,071,262.

Specification of Letters Patent. Patented Aug. 26, 1913.

Application filed October 31, 1911. Serial No. 657,707.

To all whom it may concern:

Be it known that I, JOHN H. RESE, a resident of Washington, in the District of Columbia, have invented a new and useful Improvement in Bottle-Capping Machines, of which the following is a specification.

This invention relates to bottle capping machines, and particularly to hand operated devices for sealing milk and other bottles, jars and the like, by inserting disks of paper or the like into the mouths thereof.

The object of the invention is to improve the construction and operation of such machines in order to render the same reliable, easy to operate, and capable of capping bottles while in crates so as not to necessitate the removal of the bottles therefrom, and particularly to insert in the mouths of the bottles caps or disks provided with integral tabs.

I am aware that machines have heretofore been used for putting plain round caps or disks in bottles, but I believe myself to be the first to devise a machine for inserting into bottles, caps or disks provided with integral tabs which are turned upwardly when the cap is inserted in the mouth of the bottle and serve as means for removing the cap.

The invention comprises the construction, arrangement and combination of parts hereinafter described and claimed.

In the accompanying drawings Figure 1 is a perspective view of a capping machine embodying my invention; Fig. 2 is in part a vertical central section and in part a broken out elevation thereof; Fig. 3 is a horizontal section on the line 3'-3'; Fig. 2; Fig. 4 is a plan view of the feeding slide; Fig. 5 is a detail view of the cam and gear segment; Fig. 6 is a view of one of the caps or disks; and Fig. 7 is a detail view of a spring.

The frame work of the machine may be variously constructed. As shown, the main portion of the frame is formed as a casting or stamping and comprises side pieces or uprights 1 joined at their upper ends by the cross bar 2 and further down by another cross bar 3, said cross bars being provided with suitable openings for receiving and guiding the plunger. The latter comprises two vertical rods 4 carrying at their lower ends the plunger head or disk 5 and at their upper ends having secured thereto the

handle 6. The plunger head is provided with a facing of hard rubber, leather, composition or other slightly yieldable material 7 to preclude the possibility of breaking the bottles by impact of the head therewith.

Integral with or secured to the side stands or uprights 1 is a downwardly extending tubular portion or sleeve 8, which projects down a considerable distance below the table of the machine and at its lower end is provided with a flare or bell mouth, as at 9, to guide the device upon the necks of the bottles. The bell mouth may be lined with facing material of the same character as the facing 7 and for the same reason, but this feature is not essential and I may dispense with the same.

Integral with the standards or uprights 1 is a magazine receiver or base 10 which is of general tubular form, being open on one edge, as at 11. This is adapted to receive the magazine 12 containing the paper or other disks, which magazine is of general tubular form, being provided on one edge with a projection 13 to accommodate the tabs 14 on the disks 15, and being adapted to be slipped into the magazine receiver or base in filled condition and when empty to be removed and a freshly filled tube substituted therefor. The magazine base is open on one side for the purpose of giving resiliency thereto and also to permit of the passage of the tabs on the disks. The magazines 12 are made of paper board, sheet metal or other suitable material. A weight 39 is placed on top of the uppermost disk in the magazine 90 to cause the disks to feed properly.

Located immediately below the magazine receiver or base is the table 16 of the machine. This is formed of a bottom-plate 17 and a top-plate 18, which are separated by spacers 19, preferably of the same thickness as the disks 15, to form a guide way between said top and bottom plates for the reciprocating slide 20 which carries the disks from underneath the magazine to a position underneath the plunger and over the sleeve 8. This slide is in the form of a plate provided with an opening of such size as to neatly receive the disk shown in Fig. 6. The bottom-plate 17 of the table is provided with a 105 similarly shaped opening registering with the sleeve 8, while the top-plate 18 of said table is provided with a similarly shaped

opening underneath the magazine 10 so that the disks provided with integral tabs can drop from the magazine into the opening in the slide. The opening in the slide is such 5 a distance from the end thereof that when the slide is fully retracted said end is underneath and supports the disks in the magazine. The actuating means for the slide is attached to its other end.

10 Secured to the slide 20 is the horizontal bar 21 provided on its top with rack teeth. This rack bar is engaged by a toothed gear segment 22 which is mounted at 23 between arms 24 projecting from the top cross bar 2 15 of the frame. To prevent the rack bar 21 from springing downwardly where it is engaged by the gear segment, it is supported by a small roller 25 supported by projections 26 from the lower cross bar 3 of the frame. The gear segment 22 is provided 20 with a slot having an upper cam portion 27 and a substantially straight portion 28, which slot is engaged by a roller 29 carried by arms 30 secured to a block 31 adjustably 25 mounted on the plunger rods 4 and held thereon by screws 32. The cam slot is so shaped that upon a slight depression of the plunger the gear segment is given its full throw to positively move the slide 20 to 30 carry a disk from underneath the magazine to a position underneath the plunger, and then remains stationary during the further downward movement of the plunger. The roller 29 is for the purpose of reducing friction, and is not absolutely necessary, as a pin 35 engaging the cam would produce the same movement. To retract the slide 20 for the purpose of feeding another disk or tab a spring 33 is provided having coils 34 mounted 40 upon the opposite projecting ends of the pivot 23 of segment 22. These coils are connected by a downwardly projecting loop 35 which passes through the opening 36 in segment 22 and presses against the straight 45 portion 28 thereof. The free ends 37 of the spring 33 are each bent upwardly and are fastened or connected to the arms 24, preferably by seating them in sockets therein.

It will be noted that by the construction 40 just described the spring 33 has a constant tendency to retract the slide 20 through the segment 22. At the same time it exerts force upon the handle 6 and rods 4 tending 45 to move them longitudinally or vertically only at such times as the roller 29 is engaged with the cam portion 27 of the slot in the segment. Whenever the roller 29 is engaged with the straight portion 28 of the slot, the handle, rods and disk 5 are free 55 sliding and may be moved without resistance from the spring.

The handle 6 is of loop form, as shown, so that not only can the plunger be conveniently depressed, but the whole machine can 60 be carried thereby. This handle is not sym-

metrical with reference to the plunger but projects more to one side than to the other. This is for the purpose of enabling it to clear the magazine which is placed in as close proximity to the plunger as possible, 70 as is desirable, so that the disks need not be moved any great distance. The shape of this handle is such that the machine practically balances when suspended by the handle.

In the use of the device a tube 12, filled 75 with the paper disks is inserted in the magazine receiver or base 10. The machine is then moved downwardly over the bottle with a quick movement until the neck of the 80 bottle 38 projects into the flaring end 9 of the sleeve 8. The impact of the machine with the bottle causes the roller 29 to ride down the cam portion 27 of the slot in the cam segment 22, thereby imparting the full 85 movement to the cam segment and through the rack bar drawing the slide fully back against the action of spring 33 so as to carry a disk from underneath the magazine to a 90 position underneath the plunger. During the further downward movement of the plunger the roller 29 moves down the straight portion 28 of the cam slot in the gear segment and hence causes no further 95 movement of the slide. By reason of the 100 peculiar arrangement of spring 33 the plunger at this time is free sliding and no particular exertion is necessary to lower it. In fact the weight of the head, rods and disk 105 is of itself almost sufficient to cause the plunger to drop. The plunger is now fully depressed and presses the paper disk down into the neck of the bottle and turns the tab upwardly, as will be readily understood. The 110 handle is next lifted until the roller 29 115 engages with the cam portion 27 of the slot, when the spring 33 returns the cam segment and slide to the original position. During 120 the first portion of the upward movement of the plunger the slot holds the slide stationary until the plunger head clears the feed slide, and at the uppermost portion of the movement the cam and spring return 125 the slide to position to bring the opening therein underneath the magazine to receive 130 a new cap. The device is carried from bottle to bottle and the operation repeated at each bottle. This operation can be very quickly effected and a large number of bottles can be capped by an operator in a short 135 period of time. The sleeve 8 is of such length that the device can be applied to bottles while in crates and without the necessity of removing the same from the crate. Usually the edges of the crate project somewhat above the tops of the bottles, so that the bottles next to the walls of the crate are not accessible by a flat bottomed capping device. The sleeve 8, however, is of such 140 length that the bottles at the walls of the 145

crate can be capped as readily as those farther in. This sleeve not only permits the table of the machine to lie above the top edge of the crate, but also centers the machine on the bottle.

It will be observed that by reason of the adjustability of the block 31 and roller 29 longitudinally of the rods 4, it is possible to so arrange the parts that the head 5 may be caused to project downwardly below the slide 20 various distances at the time the roller 29 seats in the lower end of the slot 28. Different makes or sizes of milk bottles, especially in different localities, vary slightly in external diameter at the mouth. The caps consequently may seat at different points vertically in the flaring of bell mouth 9. The adjustment referred to furnishes a convenient arrangement for causing the plunger to move down to proper seating position for such different sizes of bottles.

The device described is of simple construction and very easy to operate. The movements are all positive and the device can be used without fatiguing the user, the shape of the handle being such as to not only provide effective means for depressing the plunger, but also for lifting the entire machine from one bottle to the other.

While I have described a machine for inserting an integral tab, cap or disk, I do not wish to be confined to the particular showing of my invention made in the drawings hereof, as it is evident that other means can be employed, such as the machine being made in multiples and operated by foot or other power; also in place of the machine being lifted, the plunger can be operated with the same result, without departing from the spirit of the invention.

One of the caps or disks fed by the present machine is shown in Fig. 6 and comprises a body portion of regular contour, shown as round or circular, from one side of which projects an integral tab 14. As the round head 5 of the plunger forces each cap to its seat in the bottle, the tab 14 is bent upwardly or into a position normal to the body of the cap in an obvious manner.

What I claim is:—

1. In a bottle capping machine, the combination of a frame, a plunger movably mounted therein, a magazine adjacent to said plunger, a slide adapted to transfer bottle caps from the magazine to a position underneath the plunger, a rack connected to said slide, a gear segment engaging the rack, a cam and pin connection between said gear segment and plunger, whereby the movement of the plunger moves the slide to transfer a bottle cap from the magazine to a position underneath the plunger, and a spring engaging the segment for retracting the slide.

2. In a bottle capping machine, the combination of a frame, a vertically movable freely sliding plunger mounted therein, a magazine adjacent to said plunger, a slide adapted to transfer bottle caps from the magazine to a position beneath the plunger, an operating member between the slide and plunger so constructed and arranged that during the first portion of the downward movement of the plunger a cap is moved by said slide into position beneath said plunger and that movement of the slide is prevented during further movement of the plunger, and a spring on the frame operatively connected to the slide for retracting the slide when the plunger is raised.

3. In a bottle capping machine, the combination of a frame, a freely sliding plunger movably mounted therein, a magazine adjacent to said plunger, a slide adapted to transfer bottle caps from the magazine to a position in line with the plunger, an oscillating member having a spring connected thereto and arranged to move said slide in one direction, and connections between said member and the plunger whereby the plunger controls the movement of the slide in said direction and positively moves the slide in the other direction.

In testimony whereof, I have hereunto set my hand.

JOHN H. RESE.
